D 16503

UNITED STATES PATENT OFFICE.

STERLING F. HAYWARD, OF NEW YORK, N. Y.

DESIGN FOR A BOTTLE.

SPECIFICATION forming part of Design No. 16,503, dated February 2, 1886.

Application filed December 5, 1885. Serial No. 184,860. Term of patent 3½ years.

To all whom it may concern:

Be it known that I, STERLING F. HAYWARD, a citizen of the United States, residing at New York city, in the county of New York and State of New York, have invented and produced a new and original Design for Bottles, of which the following is a full, clear, and exact description, reference being had to the accompanying drawings, forming a part thereof.

10 Hand fire-grenade and other bottles have heretofore been made in a variety of shapes, with raised and depressed portions, with projecting or sunken angles, with facets of various configuration and disposition, with globular, angular, corrugated, or ribbed bodies.

15 As differentiated from these, my newly-designed bottle consists of a body having vertical peripheral projecting angular ribs terminating in angular depressions, and interposed panels, as I will now proceed to particularly set forth and claim.

Figure 1 is a side elevation of my newly-designed bottle. Fig. 2 is a similar view with the bottle turned one-quarter around from the position shown in Fig. 1. Fig. 3 is a top view, and Fig. 4 is a bottom view.

The shape of the body *a* is in general terms globular, and its periphery is made up of a series of vertical projecting angular ribs, *b*, and

flat diamond-shaped panels *c*, the ribs *b* terminating at each end in depressed angular facets *d*. The bottom *e* of the body of the bottle comprises two concentric circular elevations, *f g*, between which are radiating depressed facets *h*.

35 I claim—

1. The design for bottles, comprising vertical angular ribs projecting from the body of the bottle and terminating at each end in depressed angular facets, as shown and described. 40

2. A design for bottles, comprising vertical angular ribs projecting from the body of the bottle and terminating in depressed angular facets, and diamond-shaped flat panels on said ribs, as shown and described.

3. A design for bottles, consisting of the body *a*, the projecting angular ribs *b* on said body, the depressed angular terminals *d* of said ribs, the flat diamond-shaped panels *c*, and the depressed facets *h* on the bottom of the body, 50 substantially as shown and described.

In testimony whereof I have hereunto set my hand this 2d day of December, A. D. 1885.

STERLING F. HAYWARD.
